UNITED STATES PATENT OFFICE.

JEREMIAH CAMPBELL, OF BOSTON, MASSACHUSETTS.

MECHANISM FOR COAL-BUNKERING SHIPS.

SPECIFICATION forming part of Letters Patent No. 793,122, dated June 27, 1905.

Application filed July 5, 1904. Serial No. 215,424.

To all whom it may concern:

Be it known that I, JEREMIAH CAMPBELL, a citizen of the United States, and a resident of Boston, in the county of Suffolk and State of Massachusetts, have invented a new and useful Improvement in Mechanism for Coal-Bunkering Ships, of which the following is a specification.

In bunkering a ship at sea prior to my invention a barge was provided carrying a tower in which the coal-hoisting apparatus was located, the barge itself being sometimes filled with coal or in other cases the coal-barge being drawn alongside of it. Sometimes, also, the tower was on a barge separate and distinct from the power-barge, or if the bunkering was to be done near the wharf the engine was on the wharf and the tower on the barge. Where the tower is mounted upon a coal-barge, it must be made movable thereon in order that it may be drawn from one end of the barge to the other, according to the location of the coal-bunkers in the barge. As each bunker on the barge is emptied the tower must be relocated over a full bunker and the barge must be relocated with relation to the ship, so as to bring the tower in its new position on the barge alongside of the port through which the bunkering is being done. As I have intimated above, heretofore two movements have been necessary, and these movements have required considerable time to effect and in a day's work sometimes making serious delay. As heretofore practiced the barge had to be warped forward, for example, and when that operation was completed the tower had to be moved back, or vice versa.

My invention is intended to overcome this trouble; and it consists in means whereby the barge and tower are moved simultaneously, the barge being drawn in one direction and the tower in the other. For this purpose I provide a shaft carrying spools and capable of connection with an engine or other source of power. Supposing the spools to be four in number, as shown in the drawings, one spool carries the rope for warping the barge rearward, another spool for warping the barge

forward, a third spool for moving the tower rearward, and a fourth spool for moving the tower forward.

My invention will be understood by reference to the drawings, in which—

Figure 1 is a side elevation of a steamer and barge located in position to be operated in the manner above referred to and embodying my invention. Fig. 2 is a plan view showing a barge and a portion of a steamer. Fig. 3 is a side elevation of the barge, somewhat enlarged and less diagrammatic than the views shown in Figs. 1 and 2; and Fig. 4 is a plan of the barge.

A is the steamer, and B is the barge.

C is the "tower," which may be constructed in any of the now well-known ways, this term being used to include a crane or the like, by means of which tackle is supported to operate a grab, the grab being shown at D. The tower C is mounted on a platform C', provided with suitable wheels c, which run upon rails b on the barge B. The grab D is operated by means of hoisting and operating ropes d, which run from the grab in the usual way and over pulleys in the top of the tower and down around the pulley d' at the base of the tower and over a pulley d² to the drum d³ in the hull of the barge, which is operated by means of the engine located, for example, in the house E at the stern of the barge. Means are provided for moving the tower backward and forward along the deck of the barge as follows: F is a shaft mounted on the deck of the barge. On this shaft are mounted four freely-moving spools. Two spools G G' carry the tower-moving ropes, and the spools H H' carry ropes for warping the barge. These spools are all of the same size, and each is provided with a suitable clutch, whereby it may be connected to the shaft F to move with it, the shaft being suitably connected with the engine, as at F', so as to be reversible. The connection of the shaft with the engine is not shown in detail and need not be specifically described, as it may be an ordinary worm-and-gear connection, nor need the clutches referred to be specifically described, as any of the or-

dinary clutches suitable for heavy work will answer. The purpose of these clutches is to place the various spools within easy control and reach of the engineer. A rope g runs 5 from one end of the truck C', which carries the tower, around pulleys g' g^2 to the spool G. From the other end of the truck C' runs a rope g^3 round pulleys g^4 g^5 to the spool G'. The ropes in question are wound differently 10 upon the said spools, so that although the spools are rotated in one direction one spool will unwind while the other spool winds up its rope. Thus by rotating the shaft F in either direction and making the proper connections between the spools G and G' with 15 the shaft the location of the tower C can be changed in either direction upon the barge.

The means for changing the location of the barge with relation to the steamer comprises 20 two hawsers, one of which, h , is connected to a cleat near the bow of the steamer, preferably on one of the lower decks, and runs round a guide-pulley h' and pulleys h^2 h^3 to the spool H. The other hawser h^4 , coming from near 25 the stern of the steamer, runs round the pulley h^5 to the spool H'. These hawsers are wound upon the spools H H' in such manner that winding up the hawser upon one spool will unwind it from the other. The four 30 spools G G' H H' are all of the same diameter, so that an absolutely uniform motion may be given both to the tower and to the barge itself, and thus it may be seen that the tower may be warped toward the stern of the barge 35 at the same time as the barge itself is being warped toward the bow of the steamer and at exactly the same rate, so that the tower will not change its position with relation to the port-hole through which the bunkering is 40 taking place, and the whole operation will take place without the assistance of any deckhands on board the steamer or changing the ropes in any way, the entire situation being under the control of the engineer. As shown 45 in the drawings, the side of the barge along which the warping-hawser runs is next the steamer. Where the other side of the barge is alongside the steamer, other pulleys h^6 h^7 are used, so as to lead the hawsers in the 50 proper direction.

An examination will show the various possibilities of this invention and its value for the purposes for which it is constructed. The steamer and the barge being once located 55 alongside each other, the process of unloading from the bunkers of the barge begins in the usual manner until the particular bunker over which the tower is located is emptied. Thereupon the engineer, connecting the shaft F with 60 the engine so that it will turn in the proper direction, moves the tower and at the same time moves the barge, the tower being moved in one direction and the barge in the other at

substantially the same speed, so that the tower will not change its relation to the steamer's 65 port. When the tower has arrived over the full bunker, the shaft F is disconnected from the engine and the operation of bunkering goes on until another adjustment is needed, owing to the emptying of the second bunker 70 in the barge. If by this time the bunker on board the steamer is full, so that the entire apparatus must be moved, this can be done by connecting the spools H H' with the shaft F and without connecting the spools G G'. The 75 barge will then be moved to the next port-hole and the bunkering continued. I have shown in the drawings and have described a simple mechanism for carrying on this bunkering operation; but it is evident instead of 80 placing the engine upon the barge which carries the tower the engine may be placed upon another barge, the two barges being lashed together, the various ropes and hawsers being guided to the proper spools by suitable pulleys, or the engine being located upon the wharf the barge carrying the trolley can be warped along the wharf from one coal-pocket to another, carrying the tower by means of 85 which it is being unloaded, the ropes in this 90 case being carried to the spools on the engine by suitable guiding means.

While the tower-moving means may consist of two ropes each wound on its own spool, as shown, a single rope may be used. In this 95 case each end of the truck supporting the tower has an end of the rope attached to it, the middle of the rope being wound around a single spool. The turning of the spool in one direction will wind up the rope on one side of 100 the spool and release a corresponding amount of rope on the other side, thus changing the position of the truck and tower. In like manner a single warping-hawser may be used to operate the barge with relation to the steamer, 105 one end of the hawser being attached to the bow of the steamer and the other end to the stern thereof. These modifications are not specifically shown in the drawings, as it is believed they will be fully understood from this 110 description by those skilled in the art.

It will be understood from this description that my invention may be embodied in a variety of ways.

What I claim as my invention is—

1. In a coal-bunkering apparatus, a vessel, a barge, a tower mounted on said barge, and means whereby said barge and said vessel may be moved with relation to each other while said tower is maintained in fixed relation to 120 said vessel, as set forth.
2. In a coal-bunkering apparatus, a vessel, a barge, a tower mounted on said barge, and means whereby said tower and said barge may be simultaneously moved with relation to each 125

other and to said vessel, as and for the purposes described.

3. A coal-bunkering apparatus comprising a barge, a tower movable thereon, tower-hauling ropes and barge-warping ropes, and means, such as a shaft carrying spools of equal diameter located on said shaft whereby equal lengths

of one of said tower-hauling ropes and one of said barge-warping ropes may be taken up simultaneously.

JEREMIAH CAMPBELL.

In presence of—

GEORGE O. G. COALE,
M. V. FOLEY.
